COVER FASTENER

John Herbert Weiss, Augusta, Ga., assignor to
Leighway Fastener Company, Benton Harbor,
Mich., a corporation of Michigan

Application July 25, 1936, Serial No. 92,536

7 Claims. (Cl. 217—124)

This invention relates to cover fasteners, and more particularly to the wire fasteners employed on bushel basket covers, or on the covers for half bushel baskets, for removably securing the covers in place, after the baskets are filled.

Generally stated, the object of the invention is to provide a novel construction and arrangement whereby the ends of the wire, of the fastener members that are secured to the basket cover, are inserted between the upper edge of the cover hoop and the lower surface of the veneer strips of the cover, thereby to more firmly anchor the end portions of the wire in the materials of the cover, and also to prevent the ends 10 of the wire from scratching or injuring the hands of the workers, one kind or another, who are called upon to handle the baskets and covers. It is also an object to provide certain details and specific features of construction tending to 15 increase the general efficiency and desirability of wire basket cover fasteners of this particular character.

To the foregoing and other useful ends, the invention consists in matters hereinafter set forth and claimed and shown in the accompanying drawing, in which—

Fig. 1 is a plan view of a basket cover provided with wire fastener members embodying the principles of the invention.

Fig. 2 is an enlarged detail or fragmentary section on line 2—2 in Fig. 1 of the drawing.

Fig. 3 is a perspective of a portion of a basket cover, and the adjacent portion of the basket body, showing the two wire fastener members, one on the cover, and the other on the basket body, interconnected to hold the cover in place.

Fig. 4 is a detail or fragmentary section on line 4—4 in Fig. 3 of the drawing.

As thus illustrated, the basket cover, to which the invention is applied, comprises a preformed hoop 1, to which the flat staves or boards 2 are secured by staples 3, in the well known manner. There is a cross stave 4, fastened to the top of the cover, with projecting ends, so that these 45 ends can be inserted through the basket handles, in the well known manner.

At the opposite ends of the top stave 5, which is above the staves 2 and under the cross stave 4, wire fastener members 6 are provided, each 50 member being loop-shaped or bail-shaped in form, with the end of the loop extending beyond the end edge of the stave 5, in the manner shown. The end portions of the wire are inserted downwardly through the stave 5, and the extreme 55 end portions 7 are inserted outwardly between

the hoop 1 and the under side of the stave 5, as shown more clearly in Figs. 2 and 4 of the drawing, and as indicated in dotted lines in Fig. 3 of the drawing.

As shown in Figs. 3 and 4 of the drawing, the basket body 8 is provided with inner and outer top hoops 9 and 10, in the well known manner, and the other members 11 of the two wire cover fasteners are attached to these hoops in the manner shown, by inserting the wire inwardly, 10 and by suitably clinching the ends 12 against the inside hoop. The tonguelike loops thus formed extend straight, upwardly, from the points where they are inserted through the hoops, when the basket is ready for filling, and when the 15 cover is placed in position, as is obvious, these tongues 13 will extend upwardly through the loops 14 of the cover fastener members, and the tongues 13 are then bent down in the manner shown in Fig. 3 of the drawing.

In this way, the cover is securely, but removably, held in place on the top of the basket.

By anchoring the wire ends 7, in the manner shown and described, the fastener member 6 is less liable to pull out, when it is interconnected with the wire members on the basket body, and in addition, the ends 7 are embedded and covered in a manner to prevent them from scratching the hands of workers who have to handle the baskets and covers. In addition, it will be seen that the 20 points of downward insertion of the wire, in the sheet material 2, are co-operatively close to the points of horizontal insertion between the sheet material and the hoop, whereby the stiffness of the wire is effective to prevent loosening of the loop where it is vertically inserted in the sheet material.

Moreover, the sharp points of the wire are prevented from moving downward, when a pull is imposed on the loop, and thus 25 injury to the fruit or other contents of the basket is prevented. In other words, without the engagement of the sharp points of the wire with the hoop, there would not only be the danger of the loosening of the loop where it is inserted through the sheet material, but there would also 30 be the danger that the end portions of the wire would swing or move downward, as the result of such loosening, and would scratch or injure the 35 contents of the basket.

Thus it will be seen that an effective method 50 is provided for the disposition of the ends of a wire fastener member. As shown and described, the said fastener member is a cover fastener for a basket cover. But a staple-shaped or bale-shaped wire member, of any suitable or desired 55

form or character, for any suitable or desired purpose, may have its ends covered and disposed in position by insertion between flat material and the edge of a hoop, in order not only to 5 more thoroughly anchor the wire member in the materials, but also to protect the hands of workers against injury by the sharp ends of the wire.

Thus the tight clamping of the ends 7 on the upper edge of the hoop or strip 1, by the flat material 5, so that the member 14 will not pull out in ordinary use, is an important feature of 10 the invention.

It is also obvious that this invention relates to 15 covers having a reinforcing strip on the under side thereof, as without the reinforcing strip, such as the hoop 1, the ends of the wire could not be clamped and rigidly held in place in the manner shown and described. More specifically considered, the invention relates to basket covers 20 of the kind that have a hoop on the bottom thereof, which hoop is adapted to rest upon the round upper edge of the basket.

As shown more clearly in Fig. 2, the edge of 25 the flat material 5 preferably extends a distance beyond the hoop 1, and thus the ends of the wire terminate short of said edge, and thus do not extend beyond the outer side of said hoop.

What I claim as my invention is:

1. A cover for a shipping container, comprising 30 a reinforcing strip for the under side of the cover, adjacent the outer edge of the latter, flat sheet material resting on the upper edge of said strip, means permanently inserted downward through said material and into said strip, so that 35 the latter is permanently fastened to the under side of said material, a wire loop disposed flatwise on the upper side of the cover and projecting beyond the edge thereof, the legs of the loop extending downward through said material and 40 then outward with their ends clamped between the upper edge of said strip and the under side of said material, so that said ends are covered and tightly held against displacement when a 45 pull is exerted on said outer end of the loop, in combination with flexible means on the side of the container body for insertion upwardly through said loop, adapted to be bent down to form hook engagement with said loop.

2. A cover for a shipping container, comprising 50 a reinforcing strip for the underside of the cover, adjacent the outer edge of the latter, flat sheet material resting on the upper edge of said strip, means permanently inserted downward through said material and into said strip, so that 55 the latter is permanently fastened to the under side of said material, a wire loop disposed flatwise on the upper side of the cover and projecting beyond the outer side of said strip, the legs of the loop extending downward through said 60 material and then outward with their ends clamped between the upper edge of said strip and the under side of said material, so that said ends are covered and tightly held against dis-

placement when a pull is exerted on said outer end of the loop, in combination with flexible means on the side of the container body for insertion upwardly through said loop, adapted to be bent down to form hook engagement with 5 said loop.

3. A cover for a shipping container, comprising a reinforcing strip for the under side of the cover, adjacent the outer edge of the latter, flat sheet material resting on the upper edge of said strip, means permanently inserted downward through said material and into said strip, so that the latter is permanently fastened to the under side of said material, a wire cover fastened disposed on the upper side of the cover adjacent 10 the edge thereof, the legs of the fastener extending downward through said material and then outward with their ends clamped between the upper edge of said strip and the under side of said material, so that said ends are covered and 20 tightly held against displacement when a pull is exerted on said outer end of the fastener, in combination with flexible means on the side of the container body for insertion upwardly in 25 side said fastener, adapted to be bent down to form hook engagement with said fastener.

4. A structure as specified in claim 3, said strip comprising an annular hoop, said container body having an annular rim firmly engaging the lower edge of said hoop, and a cover 30 fastener with similarly clamped ends diametrically opposite the first mentioned clamped ends.

5. A structure as specified in claim 3, said clamped ends being parallel with and directly below the legs of said fastener. 35

6. A cover for a basket comprising a mat portion, a rim extending entirely around the said mat portion and secured thereto, and fastener elements secured to said mat portion and each comprising a U-shaped member having the 40 closed end thereof disposed above and extending outwardly beyond the edge of said mat portion for cooperation with fastener elements on the basket body and having the leg portions thereof 45 extending through and along the under surface of said mat portion and terminating between said rim and said mat portion whereby to prevent deformation of the said leg portions.

7. A cover for a basket comprising a mat portion, a rim extending entirely around the said 50 mat portion and secured thereto, and fastener elements secured to said mat portion and each comprising a U-shaped member having the closed end thereof disposed above and extending outwardly beyond the edge of said mat portion for 55 cooperation with fastener elements on the basket body and having the leg portions thereof extending through and along the under surface of said mat portion and between said rim and said mat portion whereby to prevent outward perforation 60 of said rim by the said leg portions.

JOHN HERBERT WEISS.
